UNITED STATES PATENT OFFICE

HORACE ARTHUR MARSTON, OF SUTTON, ENGLAND

BURNER FOR PULVERIZED FUEL

Application filed June 27, 1928, Serial No. 288,690, and in Great Britain July 22, 1927.

This invention relates to burners for pulverized fuel and refers to burners with which streams of air or steam under pressure are employed for breaking up the body or mass of fuel and forcing it out of the burner.

The chief object of the present invention is to improve the construction and increase the efficiency of such burners and to deliver streams of air or steam to the burner in such a manner that less horse power will be required than hitherto for supplying such streams at the necessary pressure or with the requisite velocity.

According to the present invention the fuel pipe, which is surrounded by an air or steam supply pipe, is furnished with a convenient number of spirally arranged ribs, vanes or the like all terminating at different points around the pipe and with a series of steam or air supply ports which may be within the ribs, and the surrounding air or steam supply pipe terminates at the delivery end of the fuel pipe and may be provided with an open ring with inwardly curved walls or it may comprise a series of delivery ports which do not correspond with one another axially and are preferably furnished with walls of curved formation.

Referring to the accompanying drawings:-

Fig. 1 is a longitudinal section of a burner constructed in accordance with or embodying the present invention.

Fig. 2 is a front end view of the same burner,

Fig. 3 is a longitudinal section of a modified construction of burner,

Fig. 4 is a front end view of the burner shown in Fig. 3 and

Fig. 5 is a view showing a development of the ribs illustrated in Fig. 1.

Referring first of all to the embodiment of the invention illustrated in Figs. 1 and 2, the delivery pipe A for the pulverized fuel is connected with a supply pipe A¹ and is arranged concentric with an outer pipe B through which air or steam is supplied and delivered to the fuel or fuel mixture from the pipe A, beyond the point of discharge from the pipe A.

Within the fuel supply pipe A which may be of constant or varying diameter, is a series of webs, fins or ribs A², and these are arranged spirally around the interior of the pipe at intervals which may be irregularly spaced, said ribs terminating at different distances from the outlet of the pipe A (see Figs. 1 and 5).

Opening into the fuel pipe A are air or steam supply ports A³ and conveniently these ports are formed within the ribs A² so that they enter the pipe A at different points. At their rear ends these ports communicate with the pipe B and are controlled by a rotatable valve C.

The valve C is in the form of a sleeve which is mounted to rotate on the pipe A and within an internal ring or collar b on the pipe B. The valve C is furnished with ports which can be brought into register with the inlet ends of the ports A³. This valve C can be rotated by handles C² to regulate the quantity of air or steam delivered to the ports A³ and the valve can be retained in adjusted position by a locking screw C³.

The outer air or steam delivery pipe B is conveniently furnished with a locating flange B¹ for the burner. Air or steam is supplied to the pipe B from supply pipes B² which open into the rear end of the pipe B. At the forward end of the pipe B, is mounted a ring or collar B⁶ in which are series of ports B⁴, B⁵ separated by webs B³.

The ring B⁶ rests upon the forward end of the fuel pipe A and against a sleeve A⁴ mounted thereon.

The ports B⁴ are arranged concentric with the pipe A while the ports B⁵ are arranged eccentrically to said pipe, the walls B⁷ of both series of ports being of oppositely-curved formation.

As the ports B⁴, B⁵ do not correspond axially, the fuel velocity will be retarded owing to the varying influence of the air or steam emerging from the ports B⁴ and B⁵, tangentially to the fuel stream in the case of the latter ports.

The pipe B is also furnished with a series of free air-inlet ports B⁸ arranged at spaced intervals around its circumference, and these

ports are conveniently controlled by a rotatable sleeve valve D having a corresponding series of ports D¹. Handles D² are provided for rotating this valve to regulate the supply of air to the ports B⁸.

Mounted in the fuel supply pipe A¹ to discharge into the fuel delivery pipe A is an air or steam supply pipe E which is adjustable longitudinally to regulate or vary the point of discharge relatively to the fuel pipe A and also with respect to the axis so that it may be concentric to or eccentric to the pipe A.

This pipe E, which may terminate in a hollow truncated cone or may be of fish-tail configuration, is mounted within two eccentric bushes E¹, E² which can be rotated separately or together. The pipe E is free to be slid longitudinally within the inner bush E¹ and is furnished with a stop collar E⁶.

The bush E¹ can be fixed in adjusted position by a screw E³ and the bush E² by a similar screw E⁴.

An indicator E⁵ is preferably provided so that the relative position of the bush E¹ to the pipe E can be determined easily, and the periphery of the bush E² may be marked so that its position relatively to the bush E¹ may be ascertained.

Pulverized fuel and air or steam under pressure are admitted from their respective sources of supply to the fuel pipe A and the projections or ribs A² will tend to deflect the fuel to different extents from parallelism with the axis of the pipe, resulting in the fuel trying to pass through the pipe A at different velocities due to the irregular arrangement of the ribs, though this will cease rapidly at the ends of said ribs, resulting in a retarding action on the fuel. This fuel velocity will be further reduced by the currents of air or steam under pressure issuing from the ports A³ and co-acting in imparting a varying whirling motion to the mixture passing through the pipe A. The turbulent state produced in the fuel will be extended by reason of the incoming flow of fuel and air or steam until the mixture is ejected from the pipe A. Further as the ports A³ are controllable this turbulent effect can be regulated.

The mixture, on emerging from the pipe A is subjected to a further independent agitation in the combustion chamber by the air or steam emitted under pressure from the ports B⁴, B⁵. This air or steam from the ports B⁴, B⁵ is in part diverted by the webs B⁸ and endeavours to conform to the conditions imposed by the curved walls B⁷ of the ports B⁴, B⁵ so that the turbulence created will be carried forward into the combustion chamber. The elongated outlines of the ports B⁴, B⁵ will exert an action on the stream, and part of the stream from the ports B⁴ will take a path circumferential to the fuel pipe A and

part from the ports B⁵ will take a path tangential to the pipe A.

Directional impulse may also be imparted to the fuel stream by an additional supply of air or steam from the pipe E, which, when advanced towards the pipe A, will cause the stream emerging therefrom to exert rectilinear influence on the fuel passing out of the burner and result in the length of the flame being extended into the combustion zone.

Referring now to the modified construction illustrated in Figs. 3 and 4, the steam or air supply pipe terminates in an open ring B¹ having curved walls B⁷ so that when the fuel mixture issues from the mouth of the pipe A and expands due to the increase in temperature, a converging stream of air or steam from the pipe B will impinge on it and create a turbulent effect which will reduce the velocity thereof.

The air or steam ports in this construction are not extended throughout the ribs A¹² but are connected by pipes A¹⁵ with a supply or distributing chamber A⁶ to which steam or air is supplied through pipes A⁷ from the main supply pipes B² and controlled by valves B¹².

An independent supply of air or steam may be admitted to the distributing chamber A⁶ from a supply pipe B⁹ controlled by a valve B¹⁰ and branch pipes B¹¹ which are coupled with the pipes A⁷.

When the alternative supply from the pipe B⁹ is used alone, the valves B¹² are closed and the valve B¹⁰ is opened, and when the supply from the pipe B⁹ is used in conjunction with a portion of the stream by-passed from the pipes B², the valves B¹² are adjusted to the necessary requirements, thus providing a very variable control over the turbulence produced in the fuel stream.

By adjusting the valves B¹² in conjunction with the valve B¹⁰ the intensity of the directional turbulence created in the fuel pipe A' can be varied and the direction of the fuel stream may be diverted. As in the first form, the pipe B is furnished with a circumferential series of air-inlet ports B⁸ arranged at spaced intervals, said ports being controlled by a rotatable sleeve valve D¹⁰ having ports D¹¹.

Having now particularly described and ascertained the nature of my said invention and in what manner the same is to be performed I declare that what I claim is:

1. In a pulverized fuel burner, the combination of a fuel pipe; a fluid pipe extended beyond the fuel pipe at its delivery end and surrounding said fuel pipe; and spaced hollow ribs communicating with the fluid pipe to extend angularly within the fuel pipe with their outer ends opening thereinto in the direction of the delivery end; said extended portion of the fluid pipe having eccentric

ports converging toward the delivery end of the fuel pipe.

2. In a pulverized fuel burner, the combination of a fuel pipe; a fluid pipe extended beyond the fuel pipe at its delivery end and surrounding said fuel pipe; spaced hollow ribs communicating with the fluid pipe to extend angularly within the fuel pipe with their outer ends opening thereinto in the direction of the delivery end; said extended portion of the fluid pipe having eccentric ports converging toward the delivery end of the fuel pipe; and means for controlling the flow of fluid to the ribs.

15 3. In a pulverized fuel burner; the combination of a fuel pipe; a fluid pipe extended beyond the fuel pipe at its delivery end and surrounding said fuel pipe; spaced hollow ribs communicating with the fluid pipe to extend angularly within the fuel pipe with their outer ends opening thereinto in the direction of the delivery end; said extended portion of the fluid pipe having eccentric ports directed toward the delivery end of the fuel pipe; means for controlling the flow of fluid to the ribs; and means for regulating the flow of fluid to the eccentric ports.

4. In a pulverized fuel burner; the combination of a fuel pipe; a fluid pipe extended beyond the fuel pipe at its delivery end and surrounding said fuel pipe; spaced hollow ribs communicating with the fluid pipe to extend angularly within the fuel pipe with their outer ends opening thereinto in the direction of the delivery end; said extended portion of the fluid pipe having eccentric ports directed toward the delivery end of the fuel pipe; means for controlling the flow of fluid to the ribs; means for regulating the flow of fluid to the eccentric ports; and a second fluid supply pipe arranged axially of the fuel pipe.

45 5. In a pulverized fuel burner; the combination of a fuel pipe; a fluid pipe extended beyond the fuel pipe at its delivery end and surrounding said fuel pipe; spaced hollow ribs communicating with the fluid pipe to extend angularly with the fuel pipe with their outer ends opening thereinto in the direction of the delivery end; said extended portion of the fluid pipe having eccentric ports directly toward the delivery end of the fuel pipe; means for controlling the flow of fluid to the ribs; means for regulating the flow of fluid to the eccentric ports; a second fluid pipe arranged axially of the fuel pipe; and means permitting adjustment of the second fluid pipe longitudinally of the fuel pipe.

In testimony whereof I affix my signature.

60 HORACE ARTHUR MARSTON.
